(57) **CLAIM**

The ornamental design for a table with underside fire pit as shown and described.

DESCRIPTION

FIG. 1 is a left isometric view of table with underside fire pit in a state of use.

FIG. 2 is a right isometric view of a table with underside fire pit in another state of use

FIG. 3 is a front elevational view of a table with underside fire pit.

FIG. 4 is a rear elevational view of FIG. 3.

FIG. 5 is a right elevational view of FIG. 3.

FIG. 6 is a left elevational of FIG. 3.

FIG. 7 is a top plan view of FIG. 3; and,

FIG. 8 is a bottom plan view of FIG. 3.

The table with underside fire pit may have the functionality of gas fire pit table.

The broken lines depicting the flame and rock features in FIG. 1 show an environment of a table with underside fire pit in a state of use and form no part of the claimed design. The broken lines depicting the key feature in FIG. 2 show an environment of a table with underside fire pit in another state of use and form no part of the claimed design. The remaining broken lines in FIGS. 1-8 depict portions of a table with underside fire pit that form no part of the claimed design.

1 Claim, 5 Drawing Sheets
